UNITED STATES PATENT OFFICE

97,082

DESIGN FOR AN ARTICLE OF GLASSWARE OR SIMILAR ARTICLE

Robert A. May, Washington, Pa., assignor to
Duncan & Miller Glass Company, Washington,
Pa., a corporation of Pennsylvania

Application January 25, 1935, Serial No. 55,065

Term of patent 3½ years

To all whom it may concern:

Be it known that I, Robert A. May, a citizen of the United States, residing at Washington, Pennsylvania, have invented a new, original, and ornamental Design for an Article of Glassware or Similar Article, of which the following is a specification, reference being had to the accompanying drawing, forming part thereof.

In the drawing, Figure 1 is an elevational view of an article of glassware, and Figure 2 is a bottom plan view of the article shown in Figure 1, the dominant feature of the design being the

stepped effect shown in solid lines in Figures 1 and 2 in the portion of the article underlying the upper portion which is shown in dotted lines and the design of which, in the article shown, is conventional.

The design is of wide application to articles of glassware.

I claim:

The ornamental design for an article of glassware or similar article substantially as shown and described.

ROBERT A. MAY.
